CLAIM

The ornamental design for a wrench adapter, as shown and described.

DESCRIPTION

FIG. 1 is a front-right-top perspective view of a wrench adapter showing my new design;

FIG. 2 is a front elevational view thereof;

FIG. 3 is a rear front elevational view thereof;

FIG. 4 is a left side elevational view thereof;

FIG. 5 is a right side elevational view thereof;

FIG. 6 is a top plan view thereof;

FIG. 7 is a bottom plan view thereof, and

FIG. 8 is a front-right-bottom perspective view thereof; and, FIG. 9 is a reference view thereof, showing the wrench adapter in use.

The dashed broken lines are included for the purpose of illustrating portions of the wrench adapter and form no part of the claimed design.

The dashed broken lines of FIG. 9 that make up the handle of a wrench are included for the purpose of illustrating an environmental structure and form no part of the claimed design.

The dot-dash broken lines define the bounds of the claimed design and form no part thereof.
